(57) CLAIM

The ornamental design for a personal care dispenser, as shown and described.

DESCRIPTION

FIG. 1 is a top, front, and left side perspective view of a personal care dispenser showing the new design;

FIG. 2 is a front elevational view thereof;

FIG. 3 is a rear elevational view thereof; and,

FIG. 4 is a left side elevational view thereof.

The broken lines which form the boundary of the claimed design form no part thereof. The remaining broken lines are for illustrative purposes only and form no part of the claimed design.
